United States Patent Office.

JOSEPH T. BRYAN, OF LEBANON, INDIANA.

Letters Patent No. 63,466, dated April 2, 1867.

IMPROVED GATE LATCH.

The Schedule referred to in these Letters Patent and making part of the same.

TO ALL WHOM IT MAY CONCERN:

Be it known that I, JOSEPH T. BRYAN, of Lebanon, Boone county, and State of Indiana, have invented a new and useful Gate Latch called "Excelsior;" and I do hereby declare that the following is a clear and exact description thereof, reference being had to the annexed drawings, and to the letters of reference marked thereon.

The nature of my invention consists in constructing a latch made of iron or metal. It is two by four inches. The short end, 2, is made with an inclined plane in front; the other part, 1, acts as a lever, and rests in staple 4. The latch is hinged on its bend and works freely. 3 is a staple for the catch part of the latch to work in; 5 is the catch with the inclined 6 fastened to it and screwed to the post 7.

When I want to pass the gate I raise the lever part 1 of the latch, and thereby draw the short or catch part 2 out, relieving it from the catch 5. And when the gate shuts, the catch part 2 of the lever strikes against the inclined 6 in the catch 5, and passes down on that incline until it falls into the catch 5. In this manner I close the gate.

What I claim as my invention, and desire to secure by Letters Patent of the United States, is—

The latch 1 and 2, and the connection of this latch 1 and 2 with the catch 5 and inclined 6, all operating and arranged as described and for the purpose set forth.

JOSEPH T. BRYAN.
